UNITED STATES PATENT OFFICE.

ALBERT E. KIRCHER, OF CHICAGO, ILLINOIS, ASSIGNOR TO CONTINENTAL DISTRIBUTORS, INC., OF CHICAGO, ILLINOIS, A CORPORATION OF ILLINOIS.

FIRE EXTINGUISHER.

Application filed September 15, 1917. Serial No. 191,516.

To all whom it may concern:

Be it known that I, ALBERT E. KIRCHER, a citizen of the United States, residing in Chicago, in the county of Cook and State of Illinois, have invented a new and useful Improvement in Fire Extinguishers, of which the following is a specification.

This invention relates in general to fire extinguishers and has more particular reference to extinguishers of the portable hand spring operated type, and has for its principal object the construction of an extinguisher of this character which may be charged and positioned for use with the liquid resting upon the plunger and this without danger of such liquid leaking past the plunger.

A further object of the invention is the provision of an extinguisher of this character, the parts of which will be so constructed and arranged that leakage past the plunger when the extinguisher is discharged will be eliminated or reduced to a negligible minimum.

A still further object of the invention is the provision of a new and improved valve for such an extinguisher adapted to direct the stream from the extinguisher in a form preventing it from spraying adjacent to the nozzle.

A still further object of the invention is the provision of an extinguisher of simple and economic construction composed of strong durable parts not likely to become damaged or disarranged in the use to which such extinguisher may be subjected, or to require frequent repair or replacement of said parts.

Another object of the invention is the provision of an extinguisher having a spring-driven plunger carrying a plunger stem moving through the spring, said extinguisher being provided with means for accurately guiding the plunger through the control of the movement of the stem.

A further object of the invention is the provision of an extinguisher having a small protruding discharge nozzle which may be readily aimed at the base of a fire and controllable by an operating nozzle arm following generally the contour of the discharge end of the extinguisher to permit the accurate positioning of the nozzle parts in fully

opened and fully closed relation determined by appropriately arranged indicators on the extinguisher body.

Other objects and advantages of the invention will be apparent as it is better understood from the following description when considered in connection with the accompanying drawing illustrating a preferred embodiment thereof.

On the drawing,

Fig. 1 is a side view, partially in elevation and partially in section of an extinguisher embodying my present invention;

Fig. 2 is a longitudinal section through the plunger and adjacent parts;

Fig. 3 is a similar view through a nozzle; and

Fig. 4 is a partial detailed sectional view through the refill cap.

For the purpose of illustrating my present invention I have shown on the drawing a fire extinguisher comprising a casing, having a large cylindrical portion 11 containing fire extinguishing material, and a smaller rear portion 12 containing actuating mechanism. The forward or larger portion 11 is provided at its forward end with a reduced nozzle receiving neck 13 and at its rear end is threaded on its outer face at 14 for engagement with the rear or smaller casing portion 12, the adjacent end of this latter portion flaring outwardly at 15 and providing a flange 16 carrying threads engaging the threads 14. A plunger generally indicated in Fig. 1 by reference character 17 is mounted to move in the casing part 11 and this plunger is actuated when the extinguisher is to be discharged by a pair of powerful springs 18 and 19. Said springs bearing at one end on the rear of the plunger and at the other against a disk 21 disposed at the rear end of the smaller or rear casing part 12. The end of the casing part 12 is inturned at 22 behind the disk 21 and a cap 23 is threaded over this end of the casing part 12, as indicated at 24. The plunger is provided with a stem 25 extending rearwardly and of sufficient length to permit an end 26 to protrude through the cap 23 when the plunger is retracted. The stem 25 is provided with a recess 27, adjacent the end 26 and so located as to be disposed within the cap, when the plunger is

100
105

in retracted position. A locking element 28, pivotally mounted in the cap 23 and operable by a finger piece or lever 29 is engaged in the recess of the plunger rod or stem to hold the plunger against the pressure of the spring.

Fire extinguishing liquids adapted to gaseify and form a smothering gas blanket over the fire are of penetrating character and require peculiarly tight closures to prevent leakage. In the extinguisher embodying my present invention and shown on the drawing, I have provided means for preventing the liquid leaking past the plunger, when the plunger is retracted and quiescent and means also for preventing it leaking by the plunger when the plunger is moving under the action of the springs and forcing the liquid out of the extinguisher under pressure.

The plunger consists of a body piece 31, cupped at its center to receive the springs and having an outwardly extending flange 32, slightly less in outer diameter than the inner diameter of the casing part 12. A cup washer 33 of leather or other suitable material is mounted upon the forward face of the flange 32 against which it is held by a holding annulus or disk 34 soldered or otherwise secured to the flange 32. This cup washer makes firm contact with the container wall. The means provided in the present instance for preventing leakage past the plunger when the plunger is retracted and quiescent will now be described. A ring 35 having an inwardly extending flange 36 is soldered and sweated in the rear end of the casing part 11. The flange 35 is provided with a facing or layer of lead or other soft suitable material 37 on its upper face. A spring flange or annulus 38 has one edge 39 securely fastened to the inner under edge of the flange 32 and from this inner under edge the annulus 38 extends downwardly and outwardly to above the facing 37 of the flange 36. At its outer edge a wedge shaped ring 41 is secured and extends downwardly, having a sharpened lower edge embedded in the facing 37, when the plunger is locked in retracted position. The ring 41 carries two sharpened edges, one being located within and above the other so that should the plunger be pulled back in too great degree or if through repeated use the outer lower edge cuts through or nearly through the facing 37, the inner upper edge will still be embedded in it. The ring 41 acts as a valve closing tightly against the seat provided by the flange 36 and its facing 37 and may for the purposes of this invention be considered an attachment on the plunger or as a mere part thereof.

The means for preventing passage of the liquid past the plunger when the plunger is

in action will now be described. The plunger rod in the present instance is fastened to the plunger by a lock nut 42, which engages a threaded reduced end 43 of the plunger rod, this end extending through the plunger body 31 and being preferably also threadedly engaged therewith. The lock nut 42 is provided with a central threaded aperture 44 beyond the end of the plunger rod and has a reduced portion 45 extending outwardly. A cap 46 having a peripheral flange 47 extending over and adapted to engage the cup washer 33 is held loosely on the forwardly extending reduced portion of the lock nut. A flanged collar 48 embracing the reduced portion holds the cap against outward movement and the collar is held in place by a screw 49 threaded into the aperture 44. The edge of the cup washer is beveled as indicated at 51 for engagement with the flange 47 so that when the springs are released the reacting pressure of the liquid will force the cap back against the cup washer spreading it into more tight engagement with the side of the container, the wedge shaped extremity of the cup washer not only bearing against the inner face of the container part 11 but serving also to scrape the liquid therefrom whereby substantially all of the liquid is prevented from passing the plunger.

I have also provided a new and improved nozzle adapted to prevent any leakage when both closed and open. This nozzle comprises a stationary casing part 61 having a reduced stem 62 threadedly engaged in the neck 13 of the container body. Within this casing part is mounted a quick opening valve member 63, having a tapered bore 64, providing a small outlet opening 65, which directs the stream without spraying. Two slots 66 are provided through the casing part 61, said slots being inclined and extending through approximately 90°. Two pins 67 extend out from the valve member and take into the slots, this arrangement providing a full opening and closing of the valve in a quarter turn. In assembling the valve or nozzle the valve member is positioned in the casing without the pins and the pins are then inserted through the slots. A band 68 is then soldered about the portion of the valve casing above the container end to close the opening through the slots. The inner end of the valve member is provided with a head 69, preferably of brass or other hard metal, soldered on to said valve member, openings 71 being provided through the valve member and above the head 69 to permit discharge of the liquid. The head 69 is adapted to close against the inner end of the casing member 62 to provide a seal. In order that this seal may be sufficiently tight an inset of lead 72 or other soft metal is provided in the end of

the casing member 61, which inset is adapted to be engaged by a raised edge or rib 73 on the adjacent face of the head 69. In order that no liquid may issue from the extinguisher except through the nozzle opening 65, I provide means for preventing leakage out between the valve member and the casing part 61 when the valve is open. The bore through the casing member is enlarged

10 at 74 in the forward part and the valve member is shaped to fit therein, providing a shoulder 75 on which is formed a raised edge or rib 76. This rib or edge is adapted to close against a soft metal packing 77 provided at the inner extremity of the enlargement of the bore.

15 The nozzle is adapted to be moved to open and closed positions by an operating handle or finger piece 78. This handle or finger piece carries a perforated collar 79 engaged over the outer end of the valve member, being held in place and against independent angular movement by a set screw 81. The handle or finger piece is bent at 82 to extend

20 down alongside the neck of the extinguisher and at and beyond a point 83 to follow the end configuration of the container body. At its free extremity the handle is provided with an outwardly extending wing 84 adapt-

25 ed to be engaged by the hand of the operator which is holding the forward end of the extinguisher when it is desired to use the same. In order that the extinguisher may be fully opened or completely closed upon 30 appropriate movement of the nozzle handle, indicators 85 and 86 are provided, movement of the handle over the open and shut indications bringing the valve to the desired positions, respectively and advising the operator whether the valve is open or shut. The

35 provision of these indicators also enables anyone inspecting the device to tell whether the nozzle is closed fully as it should be when the extinguisher is not in use.

40 45 In order that the plunger may be guided accurately in its opening and retractive movements, I provide a guide for the stem 25, which is located within the springs. This guide comprises a tube 87, having an end 88, secured to the disk 21 and extending into the casing part 12 a sufficient distance to remain about the stem when the plunger has 45 reached the end of its operative stroke. It is intended that the plunger be returned to 50 normal operative position by engaging a suitable tool or implement with the rear end of the plunger rod or stem, thereafter pulling the stem back until its end protrudes through the cap 23. The tube 87 forms a 55 guide for this tool or implement, thereby 60 facilitating the recharging operation.

65 In order that the nozzle may not have to be removed in recharging the extinguisher with the consequent possibility of destroying the accuracy of the indicators through the

adjustment of the nozzle to a changed position, I provided a refilling opening 89, formed by inserting a valve seat member 91 in the casing or container wall, which valve seat member is threaded internally and adapted 70 to receive a refill cap or closure 92. This cap is provided with a raised edge or rib 93 adapted to seat against a soft metal insert 94 forming a seat.

75 It is thought that the invention and many of its attendant advantages will be understood from the foregoing without further description and it will be obvious that various changes may be made in the construction and arrangement of the parts of the device, without departing from the spirit and the scope of the invention or sacrificing all of its material advantages, the form hereinbefore described being merely a preferred embodiment thereof.

80 I claim:

1. In a fire extinguisher, the combination of a container for containing a fluid fire extinguishing material, a plunger movable therein for ejecting said material, spring 90 actuating means for actuating said plunger, a seat behind said plunger, and means for holding said plunger against said seat when the extinguisher is charged.

2. In a fire extinguisher, the combination of a container adapted to contain fire extinguishing material in one end thereof, a plunger movable in said end of said container, mechanism located in the other end of said container for operating said plunger to expel said fire extinguishing material, and means behind said plunger for preventing leakage of the fire extinguishing material into the end containing said actuating mechanism.

95 3. In a fire extinguisher, the combination of a container adapted to contain fire extinguishing material in one end thereof, a plunger movable in said end of said container, mechanism located in the other end of the container for operating said plunger to expel said fire extinguishing material, and means behind said plunger for preventing leakage of the fire extinguishing material into the end containing said actuating mechanism, a part of said means being carried by said plunger.

100 105 110 115 120 125 4. In a fire extinguisher, the combination of a container, a plunger mounted therein, pressure means acting upon the rear face of said plunger, a stop within the container and against which the plunger may be seated when the extinguisher is ready for discharge, said plunger and said stop co-operating to prevent passage of penetrating fire extinguisher fluid.

5. In a fire extinguisher, the combination of a container, a plunger mounted therein, pressure means acting upon the rear face of said plunger, a stop within the container

and against which the plunger may be seated when the extinguisher is ready for discharge, the engaging parts of said plunger and stopping being composed of different metals and one said part embedding itself in the other when said plunger is seated.

6. In a fire extinguisher, the combination of a container, a plunger mounted therein, pressure means acting upon the rear face of 10 said plunger, a stop within the container and against which the plunger may be seated when the extinguisher is ready for discharge, one of the engaging parts of said plunger and stop being embedded in the other.

15 7. In a fire extinguisher, the combination of a container, a plunger mounted therein, pressure means acting upon the rear face of said plunger, a stop within the container and against which the plunger may be seated 20 when the extinguisher is ready for discharge, the interengaging parts of said stop and plunger comprising flanges angularly arranged with respect to each other.

8. In a fire extinguisher, the combination 25 of a container, a plunger mounted therein, pressure means acting upon the rear face of said plunger, a stop within the container and against which the plunger may be seated when the extinguisher is ready for discharge, 30 the interengaging parts of said stop and plunger comprising flanges angularly ar-

ranged with respect to each other, one of said flanges being sharpened at its edge and entering into the material of the other.

9. In a fire extinguisher, the combination 35 of a container, a plunger mounted therein, pressure means acting upon the rear face of said plunger, a stop within the container and against which the plunger may be seated when the extinguisher is ready for discharge, the interengaging parts of said stop and plunger comprising flanges angularly arranged with respect to each other, one of 40 said flanges having a plurality of sharpened annular edges located in different planes and adapted to become successively embedded in the other flange.

10. In a fire extinguisher, the combination 45 of a container adapted to contain fire extinguishing material, a plunger mounted therein for expelling the same, means for preventing leakage of fire extinguishing material past the plunger when the plunger is quiescent, and subsequently acting means for preventing material leaking past the 50 plunger when the plunger is operating.
